United States Patent Office

Des. 178,664
Patented Sept. 4, 1956

178,664

AIR CONDITIONING UNIT

Harlan L. Howe, De Witt, N. Y., assignor to Carrier Corporation, Syracuse, N. Y., a corporation of Delaware

Application December 1, 1955, Serial No. 39,127

Term of patent 7 years

(Cl. D62—4)

The figure is a perspective view of an air conditioning unit embodying my new design.

The side of the air conditioning unit not visible in the figure is substantially the same as the side shown.

The design for the air conditioning unit disclosed is characterized by the front portions, including the broad band, having the configurations shown.

I claim:

The ornamental design for an air conditioning unit, substantially as shown and described.
